UNITED STATES PATENT OFFICE.

EDWARD F. SMITH, OF ROCHESTER, NEW YORK, ASSIGNOR TO JOSIAH ANSTICE, OF ROCHESTER, NEW YORK.

SLICING-MACHINE.

SPECIFICATION forming part of Letters Patent No. 731,516, dated June 23, 1903.

Application filed January 24, 1901. Serial No. 44,514. (No model.)

To all whom it may concern:

Be it known that I, EDWARD F. SMITH, of Rochester, in the county of Monroe and State of New York, have invented certain new and 5 useful Improvements in Slicing-Machines; and I do hereby declare the following to be a full, clear, and exact description of the same, reference being had to the drawings forming a part of this specification and to the reference-numerals marked thereon.

My present invention relates to slicing-machines particularly adapted for slicing bread, but capable of use for slicing meat or any other material; and it has for its object to 15 provide a mechanism in which the cutting or slicing is accomplished by a relative movement of the knife and the material operated upon and in which the cutting edge of the knife is also operated at an angle to the line 20 of said movement of the material, so as to more readily sever the material even when it is comparatively soft and yielding—as, for instance, freshly-baked bread; further, to provide improved means for operating the 25 movable parts whereby the slicing operation may be accomplished with the expenditure of a small amount of power and by a movement readily accomplished by the operator.

To these ends the invention further consists in means for accomplishing the said objects and in certain improvements hereinafter described, the novel features being pointed out in the claims at the end of this specification.

35 In the accompanying drawings, Figure 1 is a front elevation of a cutting or slicing machine embodying my improvements; Fig. 2, a similar view showing the parts in a different position; Fig. 3, a vertical sectional view 40 on the line *a a* of Fig. 1; Fig. 4, a horizontal sectional view taken on the line *b b* of Fig. 1; Fig. 5, a vertical section on the line *c c* of Fig. 4; Fig. 6, a section on the line *d d* of Fig. 4.

Similar reference-numerals in the several 45 figures indicate similar parts.

The main frame of the particular embodiment of the invention shown consists of a plate or casing 1, adapted to be secured to a suitable support, as to the end of a table, and 50 provided at one end with a vertically-extending flange or side piece 2, secured in position

by suitable screws 3 extending through lugs formed thereon, said plate forming with the bottom a holder for the material, such as a loaf of bread, (indicated by 4,) that is to be operated upon. 55

5 indicates a pushing or feeding slide, movable in the side plate 2^X and between the latter and the way formed by the side plate 2, adapted to be actuated toward the front of 60 the base-plate by suitable automatic feeding devices—such, for instance, as a flexible band 6, connected thereto and extending along the bottom thereof toward the front, the end being connected to and wound upon a spring- 65 operated roller 7, similar to an ordinary sash-balance roller, mounted in a bracket or frame 8, secured by screws 9 in a recess formed in the bottom plate. Mounted upon the follower or pusher 5 is pivoted a holding-catch 70 10, the lower end of which is adapted to cooperate with the outer or rear end of the bottom of the way to hold the follower retracted against the tension of the spring-operated roller when desired to place a loaf of bread 75 therein or for any other purpose. The rear end of the band 6 is connected to a loop 12, adapted to be hooked over a stud or projection 13 on the rear of the slide, as shown particularly in Fig. 3. At the front edge of 80 the base plate or support 1 is a frame or plate 15, having a large central opening, and the upper edge 24 of which serves as a guide and support for a reciprocating carriage 20, provided at the top and bottom with 85 bearing-blocks 21, each provided with fingers 22, extending over the guide 24, and a slot for the reception of nuts or bolts 23, passing through the edges of the frame. The lower edge of the frame 20 is also provided with 90 similar bearing-blocks, the fingers of which extend upwardly and behind a guide flange or way 24^X, formed on the lower forward edge of the base-plate 1, similar to the guide 24, as shown in Figs. 3 and 6. The frame 20 is 95 provided with a vertically-extending portion or stop-plate 25, preferably nearly circular, and mounted at the center thereof upon a bolt 26 is a rotary disk 27, having at its edge the circular knife or plate 28, which may, if 100 desired, be made in sections, the cutting edge extending substantially in the plane of the rear

face of the plate 25, as shown in Fig. 4, and also very slightly forward of the plane of the face of the frame 15 and of the end of the frame 1 and the side plates 2 2² at the opposite edges 5 of the trough, as shown in Fig. 4. At its upper portion the plate 25 is braced by an arm 38, connected to the rear end of the frame 20, as shown in Figs. 1 and 6, this arm being offset out of the plane of the cutting edge of the 10 knife. The disk or wheel 27 has a bearing on a boss 29, formed at the center of the plate 25, to maintain its operation in the proper plane by affording a surface bearing removed from the stud and is also provided on its outer face with a crank-pin or stud 30, to the outer end of which is connected a crank-handle 31, by means of which the rotary cutting-knife may be operated.

32 indicates a radius-arm or link pivoted at 20 33 to the end of the frame 15 and at the opposite end loosely encircling the crank-pin 30 between the crank-handle and the cutter disk or wheel 27, the object of which is to impart a reciprocating motion to the frame when 25 the disk or wheel is rotated.

Secured to the forward end of the frame 20 is an outer gage-plate or abutment 34, provided with a foot 35, through which passes an adjusting-screw 36, operating in a slot 30 formed in a flange 37 at the lower portion of the frame, so that by loosening the screw the gage-plate may be adjusted nearer to or farther from the forward surface of the frame 15 or the outer open end of the trough into 35 which the material to be cut is placed, to thereby gage the thickness of the slices cut by the knife.

The operation of the machine will now be understood. The material to be cut, such as 40 a loaf of bread, (indicated by 4 in Fig. 4,) is placed in the trough or holder between the plates 2. The follower 5 is drawn forward by the spring-operated roller 7, so as to hold the bread forward against the gage-plate 34, 45 (when the latter is in line therewith,) said gage-plate having been adjusted to determine the thickness of the slice it is desired to cut. The parts being in the position shown in Fig. 1, the operator, grasping the crank- 50 handle, rotates the cutting-knife or the wheel, bearing it upon the carriage, and the link 32 will force the carriage forward to the position shown in Fig. 2, and thereby the cutting-blade will not only be passed across the end 55 of the loaf, cutting a slice therefrom, but the cutting edge is all the time moving rotarily, while the knife is moved bodily forward, thereby subjecting the material to a draw cut at the same time that the knife is moved 60 through it. During the cutting operation the loaf is pressed by its spring against the stop-plate 25, which, as stated, is in the plane of the cutting edge of the knife and limits its forward movement. The continuation of the 65 motion of the crank-handle in the same direction will by means of the link 32 draw the carriage back again to first position, and as

soon as the edge of the knife has cleared the face of the loaf the spring-follower will operate the latter forward into engagement with 70 the gage-plate 34 and another slice of the same thickness will be separated upon the next reciprocation of the knife-frame. It will be understood that the thickness of the slices severed can be readily altered or determined by the relative adjustment of the stop gage-plates 25 and 34.

While it is desirable that the crank-handle should be rotated continuously, and thereby cause the continuous reciprocation of the 80 carriage, as this motion is most convenient for the operator, it will be understood that an oscillatory motion could be given said handle, say, from the position shown in Fig. 1 to that shown in Fig. 2, which is sufficient 85 to cause the complete severing of the slices.

Inasmuch as only a portion of the entire periphery of the knife operates upon the material being sliced, it is only necessary to employ a segmental knife, so that for all practical purposes that segment contained between the lines *s s* indicated in Fig. 1 might be replaced by a segmental plate the edge of which is not sharpened.

Of course other forms of mechanism for reciprocating the carriage and revolving the knife could be employed; but I find in practice that the radius-arm or link connected to the rotary knife-disk and the stationary frame is very simple and well adapted for the 100 purpose, and while the operating-handle could be located directly upon the crank-pin 30, if desired, I find in practice that it is better to employ the extra crank shown, as in this construction the movement of the hand follows 105 the movement of the carriage, and said crank-arm constitutes with the link or radius-arm 32 a toggle which affords a little more power at the point where power is desirable. It will also be understood that instead of employing a knife with a smooth cutting edge the edge could be serrated or corrugated or waved after the manner of the ordinary Foster bread-knives.

Instead of the automatic feed shown the 115 gage-plate 34 could be dispensed with and the usual or any preferred form of feeding device employed for moving the loaf forward a determinate distance, though for obvious reasons I prefer the one shown.

By the use of the term "rotary" as applied to the cutting-knife I do not desire to be confined to one which necessarily makes a complete rotation at each reciprocation of the carriage, for the knife employed is preferably 125 of sufficient diameter or radius relatively to the work-holder to utilize only a portion of the periphery thereof, and also it will be understood that it is the relative movement of the knife-support and work-holder that causes 130 the severing operation.

By the employment of the plate 25 and a rotary knife having its edge offset in the plane of said plate the friction of moving

parts upon the surface of the material being cut is reduced to a minimum, as the plate 25 has a short movement in contact therewith relative to the motion of the knife.

5 I claim as my invention—

1. In a slicing-machine, the combination with a holder and a relatively transversely reciprocatory carriage or frame having a stop-plate thereon, adapted to be engaged by the 10 material to be operated upon, of a rotary knife mounted in front of the plate and having its cutting edge extending in the plane of the plate.

2. In a slicing-machine, the combination 15 with a holder and a relatively transversely reciprocatory carriage or frame having a stop-plate and gage-plate thereon arranged in different planes, of a rotary knife on the frame having the overhanging cutting edge 20 extending substantially in the plane of one of said plates.

3. In a slicing-machine, the combination 25 with a holder, an automatic feeding device therein and a relatively transversely reciprocatory carriage or frame having an inner stop-plate and an outer gage-plate thereon arranged in different planes, of a rotary knife on the frame having the overhanging cutting edge arranged in the plane of the inner 30 plate.

4. In a slicing-machine, the combination 35 with a holder, an automatic feeding device therein and a relatively, transversely reciprocatory frame having the stationary stop-plate, and the gage-plate on the frame adjustable relative to the latter, of a rotary cutting-knife on the frame having the overhanging edge arranged in the plane of the stationary stop-plate.

40 5. In a slicing-machine, the combination with a holder, and a relatively, transversely reciprocatory frame having a stop-plate, of a rotary cutting-knife journaled on the frame and having its cutting edge offset and extending in the plane of the stop-plate.

6. In a slicing-machine, the combination 45 with a main frame, and a holder thereon, of a relatively reciprocatory frame, a rotary cutting-knife thereon and a pitman connection between the knife and the main frame and eccentric of the knife center whereby the frame carrying the knife and the main frame will be reciprocated relatively during the rotation of the knife.

55 7. In a slicing-machine, the combination with a main frame and a holder thereon, of a relatively reciprocatory frame, a rotary cutting-knife journaled thereon, an eccentric pitman connection between the main frame 60 and the knife and an operating crank-handle connected to the knife whereby the frames will be reciprocated relatively when the knife is rotated.

8. In a slicing-machine, the combination 65 with a main frame, of a reciprocatory frame thereon, a rotary cutting-knife journaled on

the frame having the crank-pin, the pitman connected to the crank-pin and main frame and an operating crank-handle connected to the crank-pin and having its operating portion extending across the center of rotation 70 of the knife.

9. In a slicing-machine, the combination with the main frame having the guides at top and bottom, of the open frame sliding on the 75 guides and having the relatively adjustable offset stop-plates, of the rotary cutting-knife journaled on the sliding frame, the crank-pin thereon, the pitman connected to the pin and to the main frame, and the crank-handle 80 connected to the pin and extending across the center of the knife.

10. In a slicing-machine, the combination with a holder and spring-operated feeding devices for moving the material to be operated 85 upon, of a relatively transversely reciprocatory frame, a cutting-knife pivoted on the frame, means for simultaneously operating the frame relatively to the holder and moving the knife on its pivot and a guard for preventing contact of the material with the knife 90 in rear of the cutting edge.

11. In a slicing-machine, the combination 95 with the holder having the plate at one side and the upper and lower guides, of the transversely-movable frame operating on the guides, the rotary knife journaled on the frame, and the pitman pivoted to the knife eccentrically of its pivotal center and to the frame. 100

12. In a slicing-machine, the combination with the holder embodying the base, the plate at one side and the open frame at the end having guides at top and bottom, of the transversely-movable frame guided on the top and 105 bottom of the open frame and having the two stop-plates one in advance of the other, and a cutting-knife pivoted on the movable frame having its cutting edge arranged between the stop-plates and in line with the rearmost. 110

13. The combination with the holder and a follower movable therein, of the reciprocatory frame having the circular stop-plate, and the relatively adjustable stop-plate, the disk pivoted on the frame forward of the circular 115 stop-plate and the circular cutting-blade secured to the edge of the disk and extending substantially in the plane of the circular stop-plate.

14. The combination with the holder, the 120 open frame secured thereto having the extension at one side and the guides at top and bottom, of the transversely-reciprocatory frame sliding on the guides, the rotary cutting-knife thereon and the pitman pivoted at 125 one end to the extension on the frame, and at the other to the knife eccentrically of its pivoted center.

EDWARD F. SMITH.
